(57) **CLAIM**

The ornamental designs for a control panel, as shown and described.

DESCRIPTION

FIG. 1 is a perspective view of the control panel showing our new design;

FIG. 2 is a front view of the design of FIG. 1;

FIG. 3 is a top view of the design of FIG. 1;

FIG. 4 is a bottom view of the design of FIG. 1;

FIG. 5 is a right side view of the design of FIG. 1;

FIG. 6 is a left side view of the design of FIG. 1; and,

FIG. 7 is a rear view of the design of FIG. 1.

The broken line disclosure represents unclaimed portions of the control panel in which the design is embodied.

1 Claim, 7 Drawing Sheets(56)
